UNITED STATES PATENT OFFICE.

MASTIN E. SANDERS, OF ROSENBERG, TEXAS.

DENTAL BITE-TRAY.

1,134,017.

Specification of Letters Patent. Patented Mar. 30, 1915.

Application filed September 14, 1914. Serial No. 861,682.

To all whom it may concern:

Be it known that I, MASTIN E. SANDERS, a citizen of the United States, residing at Rosenberg, in the county of Fort Bend and State of Texas, have invented certain new and useful Improvements in Dental Bite-Trays, of which the following is a specification, reference being had to the accompanying drawings.

10 The invention has for its primary object to provide an improved bite tray, whereby the taking of the bite may be satisfactorily performed and greatly facilitated, without material discomfort or annoyance to either 15 the patient or the operator, such as is incident to the practice of the generally adopted method now in common use.

The invention has for an additional object to produce a bite tray, which is simple 20 and inexpensive in its construction and may be used in different sized mouths.

With the above and other objects in view, the invention consists in novel features of construction, combination and arrangement 25 of parts as will be hereinafter referred to and more particularly pointed out in the specification and claim.

For a full understanding of the invention, reference is to be had to the following 30 description and accompanying drawing, in which:

Figure 1 is a vertical section through a bite tray showing the same arranged in the mouth of the patient and the gums closed 35 thereon, and Figs. 2 and 3 are perspective views showing the upper and lower sides of the dental tray.

The method commonly practised by the dental profession at the present day for taking the bite is to soften by means of heat, 40 moisture, or both, some material such as dental wax, plaster of Paris, or the like, with or without a piece of wood or other hard substance arranged at the median line to arrest or stay the bite. This has always been 45 an exceedingly difficult part of the process of preparing dental plates and is the frequent cause of failure. It also requires a great deal of time and patience both on the 50 part of the operator and the patient.

The present invention is devised with a view to overcoming this difficulty. As illus-

trated in Figs. 2 and 3 of the drawing, I form my improved bite tray of dental vulcanite, modeling compound, celluloid, or 55 similar substance. It may, however, be also constructed of metal, such as aluminum, alloys of metals, or any other hard substances having the necessary qualities.

In the opposite surfaces of the body of 60 the tray indicated at 5, a groove or depression is formed. The depression 6 in the upper surface of the body 5 receiving the upper gum ridge, while the depression 7 in the lower surface of said body receives the lower 65 gum ridge. These depressions are enlarged by means of a suitable instrument, so that the gum ridges may have a play or possible movement of one quarter of an inch more or less therein, whereby the tray may be fitted 70 into different sized mouths. The thickness of the body between the upper and lower faces thereof should be equal to or a little less than the distance between the upper and lower gum ridges, when the jaws are closed, 75 so that the lips will meet properly. The body portion of the tray is, of course, properly shaped, so that it will not interfere with the other parts of the mouth.

In the use of my improved bite tray, the 80 plaster of Paris, dental wax, or other material of the usual consistency, is placed in the upper and lower gum receiving depressions 85 of the tray, the same is then placed in the patient's mouth, and when in proper position the patient is instructed to close his jaws, biting into this soft material. The tray is allowed to remain in the mouth of the patient until the impressionable material has become set, or sufficiently hardened. The 90 bite tray is then removed, the patient assisting in the removal with his tongue.

By means of my invention, above described, the process of taking the bite is rendered extremely simple and easy of accomplishment; nor is it attended with the usual discomfort to the patient generally experienced with the methods now in common use.

Owing to the extreme simplicity of my 100 invention, it will further be manifest that the same can be produced at small manufacturing cost. The device is also of great convenience and serviceability in practical

use and materially facilitates the process of making or preparing dental plates.

What I claim is:

The herein described dental bite tray consisting of a homogeneous body molded from a hard pressure resisting substance and adapted to be entirely received within the mouth of the patient, said body being provided in its upper and lower faces with con-

tinuous grooves or channels adapted to receive the respective gum ridges. 10

In testimony whereof I hereunto affix my signature in the presence of two witnesses.

MASTIN E. SANDERS.

Witnesses:

E. E. CHERNOSKY,
J. E. JUNKER.
